US0D1031967S

(12) **United States Design Patent** (10) **Patent No.:** **US D1,031,967 S**
(45) **Date of Patent:** **** Jun. 18, 2024**

(54) **SCENT DIFFUSER FOR VEHICLE**

(71) Applicants: **HYUNDAI MOTOR COMPANY**, Seoul (KR); **Kia Corporation**, Seoul (KR)

(72) Inventor: **Mi Rim Choi**, Seoul (KR)

(**) Term: **15 Years**

(21) Appl. No.: **35/516,387**

(22) Filed: **Jan. 18, 2023**

(80) **Hague Agreement Data**

Int. Filing Date: **Jan. 18, 2023**

Int. Reg. No.: **DM/226603**

Int. Reg. Date: **Jan. 18, 2023**

Int. Reg. Pub. Date: **Feb. 24, 2023**

(30) **Foreign Application Priority Data**

Aug. 12, 2022 (KR) 30-2022-0032753

(57) **CLAIM**

The ornamental design for a scent diffuser for vehicle, as shown and described.

DESCRIPTION

1. Scent diffuser for vehicle

1.1 : Perspective

1.2 : Front

1.3 : Back

1.4 : Left

1.5 : Right

1.6 : Top

1.7 : Bottom

Reproduction 1.1 is a perspective view of a scent diffuser for vehicle showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof.

(Continued)

The broken lines shown in the figures are for the purpose of illustrating portions of the scent diffuser for vehicle and form no part of the claimed design.
